UNITED STATES PATENT OFFICE.

ADOLPH PLAGMAN, OF DAVENPORT, IOWA, ASSIGNOR TO WHITE LILY MANUFACTURING COMPANY, OF DAVENPORT, IOWA, A CORPORATION OF IOWA.

GEARING FOR WASHING-MACHINES.

No. 895,585.

Specification of Letters Patent.

Patented Aug. 11, 1908.

Application filed July 20, 1907. Serial No. 384,708.

To all whom it may concern:

Be it known that I, ADOLPH PLAGMAN, a citizen of the United States, and a resident of Davenport, in the county of Scott and State of Iowa, have invented certain new and useful Improvements in Gearing for Washing-Machines, of which the following is a full, clear, and exact description.

The object of my invention is to provide a mechanism that is particularly adapted for operating the rotary reciprocal stirrer-shaft of washing machines, and is so constructed that both foot and hand power can be employed to actuate it, and impart momentum to a speeded-up fly-wheel which is utilized to assist the manual effort required for working the machine, substantially as hereinafter fully described, and as particularly pointed out in the claims.

In the drawings:—Figure 1 is a side elevation of a washing machine having my improvements applied thereto. Fig. 2 is a side elevation of the same looking at it at right angles to the view point of Fig. 1. Fig. 3 is a vertical transverse section of the lower portion of the machine drawn to a larger scale. Fig. 4 is a plan view of the underneath of the machine drawn to the same scale as Fig. 3.

Referring to the drawings A represents the tub of a washing machine, which is supported by, say four legs a, a, a, a, in the usual manner. This tub is provided with a lid or cover B, which is hinged to a wooden strip b permanently closing a segment of the top of the tub, and it has secured to it, in a plane parallel to its hinged edge, a supporting-frame C, which, preferably, extends from one edge post to the center of the lid, at which point it is provided with bearings for the vertically disposed rotary reciprocal stirrer-shaft D. The lower end of shaft D extends down into the tub and is provided with a stirrer-head d of conventional design, and its upper end extends through its bearings and has a beveled pinion e secured thereto which meshes with and is engaged by a beveled gear E on the adjacent end of a horizontally disposed drive-shaft F, which is journaled in bearings in the supporting-frame C. I prefer to so construct the supporting frame that one section thereof will be secured to the lid of the machine and the other section screwed or otherwise secured thereto and together therewith provide a chamber for said beveled gear to operate in

at one end, and a hood C' that will cover over a spur-gear f on the opposite outer end of the drive-shaft, which latter extends beyond the edge of the tub. Spur-gear f is engaged by a segmental gear G, and the hood C' is provided with wings which cover over the upper toothed edge of the latter, and hides its engagement with gear f from view.

Segmental gear G is journaled on a suitable stud projecting from a screw-plate h secured to the side of the tub, and it has a lever H projecting upwards from its boss a suitable distance above the top of the tub, by means of which it is operated. Said segmental gear also has an arm I projecting laterally from its boss, which is, preferably, integral with the rim of said gear also, and has its end farthest from said boss pivotally connected to a connecting-rod J, whose opposite end is pivotally connected to the crank-pin j of a crank 2. This crank is secured to and projects from the adjacent outer end of a horizontally disposed shaft 3, and outside of the end of the connecting-rod crank-pin j has a bicycle or other suitably shaped pedal mounted thereon, by means of which the operator, in addition to the hand power applied to lever H can exert foot power to assist in operating the machine.

Shaft 3 extends under the center of the tub and its inner end has a comparatively large gear 4 mounted thereon, the beveled teeth of which meshes with a beveled pinion 5 made integral with the lower end of the boss of a horizontally disposed fly-wheel 6 whose center of revolution alines with the axis of the tub, immediately under whose bottom said fly-wheel is located. The supporting-frame for shaft 3 and the crank, and gear 4 mounted thereon, and said fly-wheel comprises a horizontally disposed U-shaped frame 7, one of whose branches is constructed as shown in Fig. 5 and serves as a screw-plate which is screwed or otherwise secured to the underside of the tub, and has bearings in its ends for the vertical spindle 8 on which the fly-wheel is journaled in any suitable manner. From the outer end of this U-shaped frame, a hanger 9 depends the lower end of which is provided with an outwardly projecting bearing boss 10, in which the outer end of shaft 3 is journaled. From the inner end of the lower leg of said U-shaped frame a post 12 depends that has bearings 13 therein for the inner end of shaft 3, and has its lower end 110

provided with a basal flange 14 that rests on the intersection of the cross-braces 15 of the legs, and a lug 16 extending through a suitable opening in said extension and has an eye 5 therein below the plane of said intersection through which a suitable cotter pin or its equivalent may be inserted to anchor it in place. The bearing boss 10 of hanger 9 projects through an opening in a suitable metal 10 cross-piece 17, whose ends are bent so as to enable it to be secured to the inner side of the legs of the tub between which the outer end of shaft 3 is located. The supporting-frame thus constructed forms a strong and rigid 15 frame-work for shaft 3, gear 4, and the fly-wheel, and the lower part of the tub.

What I claim as new is:—

1. In mechanism for driving a washing machine the combination with a vertically disposed rotary reciprocal shaft, a transverse rotary reciprocal shaft for actuating said vertical shaft, devices operatively connecting said shafts and a pinion on the end of said transverse shaft farthest from said vertical 25 shaft, of a reciprocal lever, a segmental gear concentric to the fulcrum of and secured to said lever, an arm projecting from said gear, a fly-wheel, a drive-shaft therefor having a crank on its outer end, means operatively 30 connecting said fly-wheel and drive-shaft and a rod connecting said crank and arm.

2. In mechanism for driving a washing machine the combination with a vertically disposed rotary reciprocal shaft, a transverse 35 rotary reciprocal shaft actuating said vertical shaft, devices operatively connecting said shafts and a pinion on the end of said transverse shaft farthest from said vertical shaft, of a reciprocal lever, a segmental gear 40 concentric to the fulcrum of and secured to said lever, an arm projecting from said gear, a horizontally disposed fly-wheel, a horizontal drive-shaft therefor having a crank on its outer end, means operatively connecting said 45 fly-wheel and drive-shaft and a rod connecting said crank and arm.

3. In mechanism for driving a washing machine the combination with a vertically disposed rotary reciprocal shaft, a transverse 50 rotary reciprocal shaft for actuating said vertical shaft, devices operatively connecting said shafts and a pinion on the end of said

transverse shaft farthest from said vertical shaft, of a reciprocal lever, a segmental gear concentric to the fulcrum of and secured to 55 said lever, an arm projecting from said gear, a horizontally disposed fly-wheel the axis of which is below and alines with that of said vertical shaft, a horizontal drive-shaft therefor having a crank on its outer end, means 60 operatively connecting said fly-wheel and drive-shaft and a rod connecting said crank and arm.

4. In mechanism for driving a washing machine the combination with a suitable supporting member, a vertically disposed rotary reciprocal shaft journaled in the same, and means for actuating said vertical shaft, of a horizontally disposed drive-shaft deriving motion from said means, a horizontal fly-wheel revolved by said drive-shaft, and an integral frame comprising a U-shaped portion the upper leg of which is secured to the bottom of said supporting member and between the ends of which said fly-wheel is 75 journaled and which has parts depending from the lower leg of said U-shaped portion in which said drive-shaft is journaled.

5. In mechanism for driving a washing machine the combination with a suitable supporting member provided with supporting legs, a vertically disposed rotary reciprocal shaft journaled in said member, and means for actuating said vertical shaft, of a horizontally disposed drive-shaft deriving 85 motion from said means, a horizontal fly-wheel revolved by said drive-shaft, and an integral frame comprising a U-shaped portion the upper leg of which is secured to the underside of said supporting member and between the ends of which said fly-wheel is 90 journaled, and which has parts depending from the lower leg in which said drive-shaft is journaled and one of which alines with the axis of said fly-wheel and has its lower portion seated at the intersection of the cross-braces of the legs of said supporting member.

In testimony whereof I have hereunto set my hand and seal this 12th day of July, A. D., 1907.

ADOLPH PLAGMAN. [L. s.]
